UNITED STATES PATENT OFFICE

152,654

DESIGN FOR A HANDLE FOR A BRUSH OR SIMILAR ARTICLE

Anthony Rodriquez, Westfield, Mass.

Application January 8, 1947, Serial No. 135,999

Term of patent 14 years

(Cl. D9—2)

To all whom it may concern:

Be it known that I, Anthony Rodriquez, a citizen of the United States, residing at Westfield, in the county of Hampden and Commonwealth of Massachusetts, have invented a new, original, and ornamental Design for a Handle for a Brush or Similar Article, of which the following is a specification, reference being had to the accompanying drawings, forming part thereof.

Fig. 1 is a side view of a handle for a brush or similar article showing my new design;

Fig. 2 is a top plan view of Fig. 1;

Fig. 3 is a left hand end view of Fig. 2;

Fig. 4 is a right hand end view of Fig. 2; and

Fig. 5 is a sectional view of Fig. 1 rotated onto

its side, on the line 5—5, looking to the left hand end thereof.

I claim:

The ornamental design for a handle for a brush or similar article, as shown.

ANTHONY RODRIQUEZ.
